DESIGN FOR A DRESS

Louise Decker, New York, N. Y.

Application July 11, 1938, Serial No. 78,404

Term of patent 3½ years

To all whom it may concern:

Be it known that I, Louise Decker, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the tucked dress disclosed of the lace insertions on the shoulder yoke, waist girdle, and skirt panel sections, as shown.

I claim:

The ornamental design for a dress, substantially as shown, and described.

LOUISE DECKER.
